UNITED STATES PATENT OFFICE.

ERWIN R. STOEKLE, OF NEW YORK, N. Y., ASSIGNOR TO THE CUTLER-HAMMER MFG. CO., OF MILWAUKEE, WISCONSIN, A CORPORATION OF WISCONSIN.

THERMIONIC AMPLIFIER.

1,309,704.

Specification of Letters Patent. Patented July 15, 1919.

Application filed June 13, 1917. Serial No. 174,417.

To all whom it may concern:

Be it known that I, ERWIN R. STOEKLE, a citizen of the United States, residing at New York city, in the county of New York and 5 State of New York, have invented new and useful Improvements in Thermionic Amplifiers, of which the following is a specification.

This invention relates to thermionic amplifiers.

Amplifiers of the thermionic type usually comprise a vacuum tube containing an anode, a grid and an incandescent cathode capable of emitting electrons. The incandescent cathode usually consists of a filament heated by an electric current. In such a cathode there is a potential difference of the heating current at different points along the filament and this results in distorting 15 the electrical field between the cathode and the grid and anode. The amount of this distortion depends upon the magnitude of the potential difference of the heating current as compared to the potentials of the anode and 20 grid. In tubes designed for large thermionic currents it is necessary to have a large area of hot cathode. The current necessary to heat this large cathode area cannot be supplied at high potential without causing a 25 very great distortion of the fields between the cathode and the other electrodes. Therefore it has been necessary to introduce 30 large currents at low potential to heat the cathode but this is objectionable in that it 35 requires the use of large platinum seals to conduct the current into the tube. It has been found in practice that it is very desirable to have the incandescent cathode at a single potential at all points on its surface 40 so that the electrical fields between the cathode and grid and anode will not be distorted. Previous attempts to produce an 45 equipotential cathode have not been wholly satisfactory as they have the disadvantage among other things of requiring the use of relatively high voltages.

One object of this invention is to provide an improved amplifier having a cathode which operates at a single potential throughout its surface or area.

Another object is to provide an improved method of heating the cathode.

Another object is to provide an improved amplifier in which there will be no distortion of the fields between the cathode grid 55 and anode.

Another object is to heat the cathode by an independent gas or vapor discharge.

Another object is to provide an amplifier which is more efficient than amplifiers here- 60 tofore used.

Other objects will appear as the specification proceeds.

The invention is somewhat diagrammatically illustrated in the accompanying drawings in which:—

Figure 1 is a front elevation of a thermionic amplifier constructed in accordance with the invention.

Fig. 2 is a front elevation of an amplifier 70 differing from the amplifier shown in Fig. 1 only in structure and not in operation.

Fig. 3 is a front elevation of an amplifier having different means for heating the 75 amplifier cathode.

Fig. 4 is a front elevation of an amplifier differing from the amplifier shown in Fig. 3 only in structure and not in operation.

Fig. 5 is a front elevation of an amplifier having still different means for heating the 80 amplifier cathode, and

Figs. 6, 7 and 8 are schematic diagrams showing how the amplifiers of Figs. 1, 3 and 85 5 may be connected with other devices in the system.

The improved amplifier comprises in general a vacuum tube containing an anode, a grid and a cathode. The anode and grid may be of usual construction but the cathode is of novel construction and is heated in a 90 novel manner. The cathode divides the tube into two separate compartments. The pure electron discharge takes place in the upper compartment from the upper surface of the cathode. The lower surface of the cathode 95 is subjected to a vapor or gaseous discharge which takes place in the lower compartment from an auxiliary cathode located in this compartment. The amplifier cathode to be heated forms the anode of this auxiliary discharge. The bombardment of the back of the amplifier cathode by the negative ions of the auxiliary discharge serves to heat the cathode. The heating current for the ampli- 100

fier cathode is therefore at right angles to the cathode surface and hence there is no fall of potential along the surface.

Figs. 1 to 5 inclusive show different forms 5 of amplifiers constructed in accordance with the invention, and Figs. 6 to 8 inclusive show how some of these amplifiers may be connected in circuit with the other devices in the system.

10 In Fig. 1 the vacuum tube is shown at 1. It may be of any convenient shape. The tube is divided into two compartments 2 and 3 which are separated by the amplifier cathode 4. The cathode 4 is disk shaped and is 15 hermetically sealed in the tube. It is connected to wires 5 and 5' which lead to the outside of the tube. The compartments of the tube are highly evacuated and for this purpose small outlet tubes 6 and 7 may be 20 provided.

The grid is shown at 8. It may be of usual construction and has a mesh determined by the amplification desired. The grid is supported in proper relation with 25 the cathode 4 by arms 9 and 10. A wire 11 is electrically connected to the grid and leads to a point outside of the tube.

The anode for receiving the electrons emitted from the amplifier cathode is shown at 30 12 and may also be of the usual construction. It is supported by the arms 9 and 10 and is electrically connected with a wire 13 that extends to a point outside of the tube.

In the compartment 3 there is located a 35 mercury cathode 14 and an auxiliary starting electrode 15. Current is conducted to these electrodes by means of the conductors 16 and 17 respectively. A mercury arc may be maintained between the mercury cathode 40 14 and the lower surface of the amplifier cathode 4. The lower surface of the electrode 4 then becomes an anode for the auxiliary discharge in the compartment 3 and the upper surface of the electrode 4 45 serves as the cathode or electron emitting surface for the pure electron discharge in compartment 2. The electrode 4 will be raised to a temperature by the mercury arc which depends upon the energy supplied to 50 the arc. If desired the upper surface of the electrode 4 may be coated with alkaline earth oxids to increase its ability to emit the electrons. The walls of the tube below the cathode 4 may be depressed if desired 55 as shown at 45 to form a restricted throat for the purpose of localizing the stream of ionized vapor on the central part of the amplifier cathode. This avoids excessive heating of that portion of the cathode in contact with the walls of the tube.

60 It will now be seen that the upper surface of electrode 4 which serves as the cathode for the amplifier is an equipotential surface with respect to the grid 8 and the anode 12 and therefore the electrical

field between the cathode and these electrodes will be uniform. Furthermore the uniformity of this electrical field is not disturbed by the intensity of the auxiliary heating discharge.

70

Fig. 2 shows an amplifier which operates on the same principle as the amplifier shown in Fig. 1 but the compartments 2 and 3 are separated by a cylindrical electrode 4'. The inner surface of the electrode 4' is the anode 75 for the auxiliary heating discharge in compartment 3 and the outer surface is the cathode or the electron emitting surface for the pure electron discharge in compartment 2. The grid 8' and anode 12' are also made 80 cylindrical in shape and are supported in proper relation with the electrode 4' by means of the arms 9' and 10'. Conductors 5, 5', 11 and 13 are connected to the electrodes as in Fig. 1, and lead to points outside of the tube. The operation of this type 85 of amplifier is the same as that shown in Fig. 1.

In Fig. 3 the anode 12, grid 8, and amplifier cathode 4 are constructed and arranged in the same manner as in Fig. 1, but the auxiliary heating discharge is produced in a different manner. Instead of using a mercury arc as in Fig. 1 a gaseous discharge is employed. For this purpose a filament 18 95 is located in the compartment and current is supplied to the filament by conductors 19 and 20. The compartment 3 is filled with nitrogen, argon or other inert gas at reduced pressure. The filament when heated 100 maintains the ionization of the inert gas in compartment 3. The filament is used as a cathode for the auxiliary discharge while the amplifier cathode 4 serves as the anode for the auxiliary discharge and is heated 105 thereby. The material of which the cathode 4 is made, and the inert gas for the compartment 2, should be so chosen that the gas will not penetrate the hot cathode and destroy the vacuum in the compartment 2.

110

In Fig. 4 an amplifier is illustrated which operates on the same principles as the amplifier just described, but the electrodes are made cylindrical in shape as in Fig. 2. The filament 18' extends into the interior of the 115 cylindrical amplifier cathode 4'.

110

Fig. 5 shows an amplifier like that shown in Fig. 3, but the hot filament is replaced by an electrode 21 connected to a single conductor 22. The arc between the electrode 21 120 and the amplifier cathode 4 is started by employing a relatively high initial voltage which may be reduced after the discharge begins. One way of accomplishing this will be later explained when the external connections of this type of amplifier are described.

125

The improved amplifier may be used in any system where it is desirable to use a device of this character. The external connections will depend largely upon the type 130

of system in which the amplifier is used. However Figs. 6, 7 and 8 illustrate one way in which each of the three different types of amplifiers above described may be connected with the circuit whose energy variations are to be amplified, and the circuit of the amplified energy variations.

Fig. 6 shows the external connections for the type of amplifier illustrated in Figs. 1 and 2, while Fig. 7 shows the external connections for the type of amplifier illustrated in Figs. 3 and 4, and Fig. 8 shows the external connections for the type of amplifier shown in Fig. 5.

In Fig. 6 the proper terminals of a battery 23 are connected to the anode 12 and cathode 4 by conductors 24, 25 and 26. The battery is in series with terminals 27 and 28 to which is connected the circuit in which it is desired to amplify the energy variations. The grid 8 is connected to the negative terminal of a battery 29 by a conductor 30. The positive terminal of the battery 29 is connected to a terminal 31. The cathode 4 is connected by a conductor 32 to a terminal 33. The terminals 31 and 33 are connected to the circuit carrying the small energy variations which are to be amplified. The battery 34 maintains the mercury arc between the mercury cathode 14 and the amplifier cathode 4, a variable resistance 35 in series with the arc being provided to control the intensity of the arc and therefore the temperature of the cathode. A switch 36 is provided to temporarily supply current to the auxiliary starting electrode 15.

In Fig. 7 the connections for the amplifier proper are the same as in Fig. 6, but the connections for the auxiliary heating discharge are somewhat different. In this figure the filament 18 is connected across part of the battery 34 by conductors 37, 38 and 39. The other part of the battery 34 maintains the amplifier cathode 4 at a positive potential with respect to filament 18, so as to set up a stream of ionized gas between the filament and amplifier cathode for the purpose of heating the latter. Variable resistances 40 are provided to vary the temperature of the amplifier cathode 4 by varying the intensity of the stream of ionized gas passing between the filament 18 and the cathode 4.

In Fig. 8 the connections for the amplifier proper are the same as in Figs. 6 and 7, but the connections for the auxiliary heating discharge are as follows:

The battery 34 is connected to the amplifier cathode 4 and the electrode 21 in the same manner as it is connected to the corresponding electrodes in Fig. 6, the variable resistance 35 being provided to vary the temperature of the amplifier cathode 4 by varying the intensity of the stream of ionized gas from the electrode 21. In order to start the dis-

charge in this type of amplifier it is necessary to raise the potential between the electrode 21 and the amplifier cathode 4 above the value required for normal operation. In order to supply this starting potential a switch 41 and inductance 42 are shunted around the battery 34 by conductors 43 and 44. When the switch 41 is closed it connects the inductance 42 across the battery 34 and when the switch 41 is opened the self induced electromotive force sufficiently raises the potential between electrode 21 and amplifier cathode 4 to start the arc. After the arc is established the potential of the battery 34 is sufficient to maintain the arc.

It will now be seen that in all of the forms of the amplifier above described the amplifier cathode is heated in such a manner that it operates at a single potential throughout its area because the heating current is substantially at right angles to the cathode surface. There will therefore be no distortion of the fields between the amplifier electrodes even when a relatively high heating current is employed. This result is obtained by the use of an auxiliary vapor or gaseous discharge in a separate compartment of the amplifier. The auxiliary discharge is therefore entirely independent of the pure electron discharge of the amplifier and does not require the use of relative high voltages. The amplifier is therefore more efficient than any heretofore devised.

The various electrodes may be made of any desired shape, the flat and cylindrical types of electrodes being herein illustrated merely to show that the exact shape of the electrodes is immaterial to the invention. Furthermore, other means, within the scope of the invention, may be devised for heating the cathode to produce the results herein described and therefore I do not wish to limit myself to the exact means or method disclosed.

Although the improved method of and means for heating the cathode have been described in connection with the cathode of a thermionic amplifier, it may be found useful in other relations and therefore I do not wish to limit myself to its use in connection with amplifiers.

What I claim is:

1. The method of heating the cathode of a thermionic amplifier or the like, which consists in generating an auxiliary gas or vapor discharge which is independent of the main discharge and of which said cathode serves as the anode.

2. The method of heating the cathode of a thermionic amplifier or the like, which consists in subjecting said cathode to a gas or vapor discharge which is independent of the main discharge of the amplifier.

3. The method of heating the cathode of a thermionic amplifier or the like, which

consists in subjecting said cathode to a gas or vapor discharge which is separate and distinct from the main discharge of the amplifier.

5. 4. The combination with the cathode of an electrical discharge device, of means for heating said cathode comprising means for generating a gas or vapor discharge which is independent of the main discharge and of 10 which said cathode serves as the anode.

5. An electrical discharge device comprising a tube having two separate non-communicating compartments, a plurality of electrodes in one compartment comprising 15 an electron emitting cathode, and means in the other compartment for generating a gas or vapor discharge which serves to heat said cathode.

6. An electrical discharge device comprising 20 a tube having two separate non-communicating compartments, a plurality of electrodes in one compartment comprising an electron emitting cathode, and means in

the other compartment for producing a gas or vapor discharge to heat said cathode. 25

7. A thermionic amplifier comprising a tube, an amplifier cathode dividing said tube into two separate non-communicating compartments, amplifier electrodes at one side of said cathode, and means at the other side 30 of said amplifier cathode for producing a gas or vapor discharge to heat said amplifier cathode.

8. A thermionic amplifier comprising a tube divided into two non-communicating 35 compartments, the first compartment containing an anode, a grid, and a cathode, said cathode having one surface exposed to the interior of said first compartment and another surface exposed to the interior of the 40 second compartment, and means located in said second compartment for producing a gas or vapor discharge to heat said cathode.

In witness whereof, I have hereunto subscribed my name.

ERWIN R. STOEKLE.
